UNITED STATES PATENT OFFICE.

JOHN S. HOUSMAN, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING LOOSE MATERIAL.

Application filed October 15, 1921. Serial No. 507,857.

To all whom it may concern:

Be it known that I, JOHN S. HOUSMAN, a citizen of the United States, residing at Chicago, in the county of Cook and State of Illinois, have invented an Improvement in Apparatus for Handling Loose Material, of which the following is a specification.

This invention relates to improvements in apparatus for handling loose material and has for its principal object to produce a new and useful apparatus of the class described and an improved method of operating the same.

The invention may best be understood by reference to the accompanying drawings, in which Figure 1 is a plan view illustrating a typical installation of my improved apparatus in a mine.

Fig. 2 is a side view of the apparatus shown in Fig. 1.

Fig. 3 is an enlarged side view of the guide.

Fig. 4 is an enlarged cross-section of the guide and jack constituting a portion of the present invention.

One of the common practices in mining operations is to advance the work along a comparatively narrow room, as for instance, when forming entries in a mine, or when removing material by small sections or "slices." Such rooms are formed by advancing the end wall or working face in any one of several well-known methods, such as pick mining or blasting. The loose material from the working face is broken down and deposited in a pile on the floor of the mine adjacent the face, as is shown in Figs. 1 and 2, in which 1 indicates the working face of the room, 2, 2, the side walls thereof, and 3 a pile of loose material resulting from breaking down the working face.

Among the many methods of removing the loose material heretofore employed is that of employing a draft operated scraper which is reciprocably moved on the mine floor to gather the material and transport it to the mine cars. My improved apparatus is designed to use with scraper devices of the class described, and provides a novel means for anchoring the advance guide for the draft ropes adjacent the working face, together with means affording lateral movement of the advance guide so that the path of movement of the scraper may be shifted

laterally and collect material at various places across the room.

In order to illustrate my apparatus, I have shown a type of scraper having a head rope 5 and a tail rope 6, and provided with a pair of pivoted rear end portions 7, 7, operatively connected with the head rope and tail rope so as to be opened when the scraper is pulled rearwardly, and to be closed by tension on the head rope 5 when the scraper is moved forwardly. It will be understood, however, that any other suitable form of reciprocating scraper may be utilized as desired.

With scrapers of the general class above described, it is necessary to provide a suitable advance guide, such as a sheave or its equivalent, anchored at or near the working face 1, so that the tail rope 6 may be trained over it to draw the scraper rearwardly as near as is practicable to the working face. As heretofore practiced, guides have been attached to a mine jack of the usual type and the jack has been fixed in a generally vertical direction so as to engage between the roof and the floor of the mine, or in some instances, at an incline between the roof and the working face, or the working face and the floor. Another method has been to fix a guide directly to the working face by embedding an anchor in the mine wall. Such devices, however, have proven unsatisfactory for one reason or another. In using mine jacks it is usually difficult to find a suitable place for firmly fixing the jack, particularly when the jack has its lower end engaging the floor, in which case it is necessary to dig out the loose material adjacent the face of the mine to get a firm footing. Furthermore, in all of the methods heretofore employed, it has been necessary to shift the position of the anchoring means of the guide several times during the gathering of the pile, in order to allow the scraper to dig at various points across the room.

Referring now to my improved apparatus, I provide a jack 8 comprising an elongated body portion 9, a telescoping pick portion 10 at one end thereof, and a screw device 11 adjacent the opposite end thereof. A series of holes 10^a, 10^b are provided in the pick portion 10, and arranged to register with a pin 10^b on the jack 9 to adjust the length of the jack. The screw device 11

may comprise any suitably operated mechanism adapted to expand the jack longitudinally so as to engage the opposite ends 12, 12, of the jack with the side walls 2, 2. 5 In the embodiment illustrated, this screw member comprises a shaft 13 having threaded engagement with a sleeve 14 abutting against one end of the body portion 9 of the jack and provided with a hand wheel 15 for 10 operating the same. A guide member 16 is mounted on the body portion 9 of the jack and movable therealong into any desired position. Said guide member comprises a sleeve 17 preferably provided with a semi-circular guard 18. A sheave 19 is rotatably mounted within said guard and is retained in place by a ring 20 having threaded engagement with the sleeve 17, and provided with a radially extending arm 21 for 15 screwing the ring when it is desired to remove the sheave 19 from the guard 18. Means for oiling the sheave comprises an annular recess 22 formed in the hub of said sheave and having an oil plug 24 communicating therewith. The entire guide member 16 is adjustable in any desired position along the body member 9 of the jack as already described, and is provided with suitable means for holding it in position such 20 as a set screw 25 carried by the sleeve 17.

The use and operation of my device is as follows: After the loose material has been dislodged from the working face into a pile 3, the jack 8 is placed transversely of the entry or "slice" adjacent and substantially parallel with the working face. The jack is readily put into position above the top of the pile of loose material 3, as indicated in Fig. 2, so that the ends 12, 12, have 25 a firm foundation in the side walls 2, 2. The tail rope 6 connected with the scraper is trained over the pulley 19 by removing the ring 20 and sliding the sheave 19 laterally from under the guard 18 a sufficient dis-

tance to receive the tail rope. The sheave 45 19 and ring 20 are then replaced to their normal positions shown in Fig. 4, so that the tail rope 6 will be maintained from accidental displacement by the guard 18. The device is then ready for operation. The 50 scraper is moved reciprocably to gather material in the usual manner. It is desirable, however, to change the path of movement of the scraper from time to time and this may be accomplished by sliding the guide member 55 16 laterally along the jack 8 to any desired position.

Although I have shown and described one form in which my invention may be embodied, it will be understood that many other means may be employed for accomplishing the same results without departing from the spirit and scope of my invention. My improved apparatus may also be advantageously applied to uses other than that shown and described herein. I do not therefore wish to be understood as limiting myself to the specific construction or use illustrated herein excepting as specifically limited in the appended claim.

I claim as my invention:

In an advance guide for a reciprocably operated scraper, the combination of a jack adapted to be fixed between lateral abutments, comprising a telescoping pick portion at one end thereof and a screw device adjacent the opposite end thereof, a sleeve member slidably mounted on said jack, a rope guard on said sleeve, a rope sheave loosely mounted coaxially with said sleeve and within said guard, and means for securing said sleeve member in a plurality of positions along said jack.

Signed at Chicago, in the county of Cook and State of Illinois, this thirteenth day of October, 1921.

JOHN S. HOUSMAN.
